UNITED STATES PATENT OFFICE.

ARTURO VILASECA Y VELASCO, OF BARCELONA, SPAIN.

GAME-COUNTER.

SPECIFICATION forming part of Letters Patent No. 447,454, dated March 3, 1891.

Application filed November 20, 1890. Serial No. 372,112. (No model.) Patented in Spain May 24, 1890, No. 10,843, and in France September 29, 1890.

To all whom it may concern:

Be it known that I, ARTURO VILASECA Y VELASCO, a subject of the King of Spain, residing at the city of Barcelona, Spain, have 5 invented certain new and useful Improvements in Marking Apparatus for Billiards, &c., (for which I have obtained a patent in Spain, No. 10,843, dated May 24, 1890, and in France, September 29, 1890,) of which the following is a specification.

My invention relates to registering apparatus adapted to be attached to or incased in one of the cushion-rails of a billiard, bagatelle, or other similar table, and it is especially applicable to so-called "carom" billiard-tables.

The principal objects of my present invention are, first, to provide a billiard, bagatelle, or other similar table with simple, durable, 20 and convenient counting apparatus for registering the points made by the player; and, second, to so arrange the counting apparatus with relation to the table as not to annoy the players or embarrass the freedom of their 25 movements.

My invention consists in certain improvements in marking apparatus hereinafter described and pointed out in the claim.

The nature and objects of my present invention will be more fully understood from 30 the following description, taken in connection with the accompanying drawings, forming part hereof, and in which—

Figure 1 is a top or plan view of a portion 35 of the cushion-rail of a table, showing one form of my improved registering apparatus in application thereto. Fig. 2 is a transverse sectional view on the line $x-x$ of Fig. 1, and Fig. 3 is a similar sectional view on the line 40 $y-y$ of Fig. 1.

In the drawings, H is a portion of the cushion-rail of a billiard, bagatelle, or other table having the cushion removed therefrom.

h is a recess or cavity cut or otherwise 45 formed preferably in the upper surface of the cushion-rail H .

A is a plate located above the recess h and mounted flush with the upper surface of the cushion-rail H .

50 K are screws for retaining the plate A to place and for permitting of its removal for repairs or other purposes.

B and C are slots formed in the plate A and adapted for the reception of the two series of balls I and I' .

55

F and F' are lugs located at or near the respective extremities of the slot C and attached to or formed integral with the plate A .

D and D' are lugs located at or near the respective extremities of the slot B and attached to or formed integral with the said plate A .

G is a rod or carrier passing through the series of balls I and attached to the lugs F and F' by means of the head G' and nut G^2 .

65

E is a rod or carrier passing through the series of balls I' , I^2 , and I^3 , and attached to the lugs D by means of a head E' and nut E^2 .

In use the series of balls I represent units, and the series of balls I' , I^2 , and I^3 represent 70 multiples thereof, so that whenever a player scores a point in the game he registers the same by transferring one of the series of balls I to the right or to the left by means of the finger or in any other convenient manner. As soon as all the balls comprising the series I have been transferred in the manner above described, one of the balls of the other series—for example, the ball I' —is transferred 75 in a similar manner, and the series of balls I are returned to their initial position.

By providing one marking apparatus for 80 each player and by operating the two series of balls in the above-described manner a complete register or score made by each player is registered, as will be readily understood.

Having thus described the nature and objects of my invention, what I claim as new, and desire to secure by Letters Patent, is—

A billiard or bagatelle table provided with 85 a recessed rail or rim, a slotted plate provided with end lugs secured into the recessed portion of said rail or rim, rods or bars supported in the lugs of said plate, and nuts applied at each end of said rods or bars, and balls 90 mounted on said rods or bars and accessible from the face of said slotted plate, all arranged in the manner shown, and for the purposes described.
